ELECTRICAL APPARATUS AND METHODS

Edgar E. Littlefield, 834 N. Stanley Ave., West Hollywood, Calif.; Effie Dora Jones Littlefield, executrix of said Edgar E. Littlefield, deceased

Continuation of abandoned application Ser. No. 344,933, Mar. 27, 1953, which is a continuation of application Ser. No. 583,327, Mar. 17, 1945. This application Apr. 13, 1954, Ser. No. 422,842

7 Claims. (Cl. 121—38)

Briefly considered the invention relates to an improved system of control and to certain improvements in the elements making up the system.

One of the objects is to provide an improved flushing system, while an additional object is the provision of an improved valve for use in the same or for such other uses as may be found for it.

Besides reducing the heating effect to a minimum, the valve in question possesses numerous advantages, including a simplified construction that in operation is quick acting and does not permit leakage when closed. Moreover, the valve seats without an objectionable hammer blow, and does not stick under ordinary use.

Certain modifications will appear in the drawings.

Numerous objects and advantages of the improvements will become obvious upon consideration of the following description and the accompanying drawings.

Fig. 1 shows an improved electrical control system, with one form of improved valve incorporated therein, the latter being shown partly in cross-sectional elevation.

In Fig. 2 is shown a modified form of valve element and piston which may be employed in the valve combination.

In Fig. 3 is shown a section *a* of urinal, partly cut away, of a type more completely described in certain prior patents issued to me, including U.S. Patent No. 1,709,083, in which type the waste deposited forms an electrical conductor in the path of a controlling circuit.

In Fig. 4 is shown, partly in cross-sectional elevation, the upper part of a modified valve construction.

Figure 5 is an enlarged vertical sectional view, with parts broken away, of a detail of certain features shown in the upper portion of Figure 4, and Figure 6 is a similar showing similarly related to Figure 1.

In the various views like numerals refer to like parts.

An arrow, Fig. 1, indicates direction of fluid flow.

Referring to Fig. 1, a step-down transformer 1, having primary and secondary windings 2 and 3, respectively, is connected with a suitable source of current, such as an ordinary alternating current service main, by means of circuit 4, having switch elements 5 and 6 therein, and additional switch elements 7 and 8, which are normally closed, so that when element 6 is open and 5 closed, the load current flowing in circuit 4 supplies heat for the coil 9 encircling the movable contact arm 10 of a temperature responsive device 11, causing the former to move into contact with terminal 12, thus closing branch circuit 13 on the secondary side of the transformer. By closing the switch 6 and opening 7 and 8 the temperature responsive device may be made to respond to heat obtained from an extraneous source or to that obtained from the secondary side of the transformer. Obviously, the primary winding 2 of the transformer is connected for energization by circuit 4.

On the secondary side of the transformer, and to the secondary winding 3, is connected secondary circuit 14, having branches 13, 15, 16 and 17, the latter being con-

2

trolled by means of a relay 18, preferably of the Telecode or equivalent type, which, in turn, is controlled by the electrodes 21 and 22 together with the fluid which at times is interposed therebetween. In case it is desired to cut out relay 18, switch element 19, which is normally open when the relay is used, may be closed. Instead of the means indicated, or as additional means therefor, the valve operating circuit may be controlled by means of a push button 20, through branch circuit 16. Circuit interruptors 23 and 24, normally closed, provide means for opening their respective circuits when desirable or necessary. Under the arrangement shown, i.e., with switch 6 open, and 7 and 8 closed, the coil 9 is heated by primary circuit 4. However, with switch 25 closed, as well as interrupter 6, and 7 or 8, or both, opened, as well as 23, the coil 9 may be heated by circuit 15.

In this way heat may be applied to the coil 9 from the low tension side of the transformer, the voltage of which, at least for certain purposes, is preferably 18 to 24 volts, or less. A transformer supplying from 50 to 150 watts has been found suitable for quite a number of purposes. The operation of the flushing system, as such, will be appreciated by reference to the above indicated patents. The Telecode relay referred to is the trade name of a relay manufactured by the Benjamin Electric Mfg. Co., of Des Plaines, Ill., and is made in accordance with the disclosure of U.S. Patent 1,272,432 of July 16, 1918.

Included in circuit 14 is a valve 26 which is also shown and described in my Patent, 1,862,937 and which has been found satisfactory when incorporated in the above combination. The housing 27 is provided with a seat 28 and a bonnet 29, with a cylindrical extension 30, and an extension at the top in the form of a tubular member 31, closed at the top, said parts being formed of brass or other non-magnetizable materials.

Arranged to co-operate with seat 28 is a piston valve 32 having a tubular extension 33, formed integral with the former, or as a separate element, and threaded therein, if desired, the tubular extension 33 having a seat 34 at its upper end, said parts being formed of non-magnetizable material of any suitable type. The tubular extension and piston provide a by-pass 35 within which a valve stem 36 reciprocates and which is resiliently mounted at the lower end by means of a coiled spring 37 and lock nuts 38. At the upper end of the valve stem a valve member 39 preferably formed of stainless iron is secured, by a threaded connection or otherwise, as desired, and arranged to co-operate with the seat 34. Resting on the upper end of the tubular extension 33 is a lever device 40 formed of magnetizable material, preferably stainless iron, and having an adjustable head 41 threaded thereon. Obviously, the threaded arrangement permits certain adjustments to be made when desirable or necessary. Head 41 is preferably formed of non-magnetic material.

The valve stem 36 and valve 39 obviously may be formed of one piece of stainless iron or its equivalent and assembled as a unit in the valve combination, thus simplifying manufacturing procedure. As indicated above, valve 39, as well as its stem, if desired, and lever arm 40 are preferably made of stainless iron or its equivalent.

A coil 42, having a core member 43, is adjustably mounted, as with set screw 31', on the tubular extension 31, in position, when energized, to attract lever arm 40, when the piston valve is in seated position. For illustrative purposes, the piston valve is shown in elevated position. The coil may be adjusted to any desired position on the extension 31. Obviously, the arrangement should be such that during the operation of the valve the

lever arm 40 slides along the wall of the tubular extension 31 adjacent core 43.

If we assume that the main valve is closed or in seated position and that energy is applied to the coil 42, the same having previously been adjusted to the most efficient position on the stem 31, the arm 40 will be attracted to the core 43, thus unseating the by-pass valve 39 and opening by-pass 35, permitting release of pressure from chamber 44, causing the piston valve to be unseated.

By modifying the construction of the piston valve 32 somewhat, as in Fig. 2, the part forming the valve head 45 may be adjustably threaded on to the stem part 46, thus permitting regulation of the fluid flow. Obviously, the extension has an additional use as an aspirator, to aid in reducing the pressure in chamber 44.

A section of an earthenware urinal bowl, shown in Fig. 3, is provided with a pair of electrodes 21 and 22, having corrosion resisting heads 48, with threaded extensions 49, on which are threaded female nuts 50. To the lower ends of these are threaded a couple of terminal nuts 51. Obviously, when liquid excreta is interposed between electrodes 21 and 22, included in circuit 14, as explained in the patents referred to, circuit 14 is closed, resulting in a flushing operation. A couple of rubber gaskets 52 prevent leakage of fluid through the holes in the earthenware bowl, while short-circuiting of the electrodes outside the bowl is prevented by means of the annular extension 53 of the bowl.

Figures 4 and 5 illustrate a sectional view of a valve, shown partly cut away, similar to the type shown in Fig. 1 of my Patent 1,862,937, the detail being of the structure cooperating with the upper end of a fluid operated piston valve 55. The tubular member 54 may be threaded into the piston part 55, or made integral therewith, as desired. Within the tubular extension 54 is a tubular extension 56, of the piston valve 55, which extension may be formed integral therewith, or as a separate piece threaded into the piston valve. The piston itself and main valve, of course, supply the remainder of the by-pass. At the upper end of the member 56 is a seat 57 for a pilot valve 58 arranged to co-operate with a magnetizable plug or core member 59, preferably made of stainless iron or equivalent, which rests on the upper end of the member 54, the latter, as well as member 56, being formed of non-magnetizable material. Pilot valve 58, 45 obviously, is preferably formed of stainless iron or equivalent. The valve is shown in elevated or open position. A coil 60 is adjustably mounted on the extension 61 of the bonnet 62. An opening 63 in the side wall of member 54 provides for communication with the by-pass through the piston. When the main valve is closed the pilot valve 58 rests on its seat 57, while the core member 59 rests on the upper end of the tubular member 54, moving freely therewith. It will be understood that the bonnet 62, together with extension 61, are formed of brass or other non-magnetizable material. The valve 17, Fig. 1, of U.S. Patent 1,862,937 is similar to and functions substantially like valve 58 above. Attention is directed to it for general information.

In the seated position of the main valve the magnetizable parts 58 and 59 will occupy positions within the coil 60 in such a way that a maximum magnetizing effect may be applied thereto. However, upon operation of the valve, these magnetizable parts move to a position designed to develop such reactance in the coil that overheating is prevented. Much less electrical energy is required to hold the valve open than is required to open it. This type of valve may, if desired, under certain conditions, be substituted for the one previously described. I have found it desirable, in certain instances, to employ an auxiliary or pilot valve the weight of which is less than that of the valve it controls. It is also desirable under certain conditions to have the auxiliary or pilot valve displace less fluid than the controlled valve.

The present application was filed April 13, 1954, as a continuation of the then pending parent application Serial No. 344,933 (later abandoned), which latter application was filed March 27, 1953, as a continuation of application Serial No. 583,327, filed March 17, 1945 (later abandoned); the last mentioned application was, in turn, a continuation-in-part of application Serial No. 333,696, filed May 6, 1940, which issued as Patent No. 2,373,697 on April 17, 1945. Serial No. 333,696, was a substitute of Serial No. 616,955, filed June 13, 1932 (later abandoned), and the last mentioned application was a continuation-in-part of Serial No. 54,080, filed September 2, 1925, which application eventuated in Patent No. 1,862,937, dated June 14, 1932.

The present application also contains matter in common with my copending application Serial No. 380,707, filed September 17, 1953.

Referring again to the combination of Fig. 1, it is obvious that, while I have illustrated and described certain means for unseating the auxiliary valve 39, other means may also be employed. A hook and eye connection, for instance, or the equivalent thereof, between the arm 40 and valve 39 may be used, if desired. A partial sectional view of an assembly of this sort is shown in Fig. 6.

For the sake of brevity I have illustrated only a few simple embodiments of my invention and the several features thereof, and have described them with particularity; but it will of course be understood that my invention is not limited to the forms thus illustrated, as I intend to cover all forms, methods, and arrangements that come within the definitions of my invention as set forth in the appended claims.

I claim:

1. The method of controlling a translating device which includes exposing a movable magnetic element to substantially the densest part of a magnetic field to move the said element and thereby to effect primary control of said device and thereafter reducing the strength of said field effective upon said element by increasing the air gap through which the field operates while maintaining said element in primary control of said device.

2. The method of controlling a translating device which includes exposing a movable magnetic element to substantially the densest part of a magnetic field to move the said element and thereby to effect primary control of said device and thereafter moving said element to a substantially less dense portion of said field beyond the densest part of said field.

3. The method of controlling a translating device which includes exposing a movable magnetic element to substantially the densest part of a magnetic field to move the said element and moving said element to a substantially less dense portion of said field beyond said densest part of said field before utilizing said element for further control of said device.

4. The method of controlling a translating device having a movable magnetic element disposed to respond to the densest part of the magnetic field provided by a companion member which includes exposing said element to the influence of said field to move said element to a predetermined position and thereafter reducing the strength of the field effective on said element by increasing the space area through which the field functions.

5. The method of controlling a translating device which includes exposing a movable magnetic element, forming a component part of said device, to substantially the densest part of a magnetic field provided by a companion member, to thereby cause said element to move to a predetermined position under the influence of said field; and thereafter causing said element to move to a substantially less dense portion of said field beyond said predetermined position.

6. The method of controlling an electro-mechanical device which includes exposing a movable magnetic ele-

ment, forming a component part of said device, to substantially the densest part of a magnetic field provided by a companion member to thereby move said element to a predetermined position to thereby effect initial control of said device and thereafter reducing the strength of said field effective on said element by moving the element to a predetermined position beyond its last previous position.

7. The method of reducing the heating effect of alternating current on a translating device having a movable magnetic element disposed to respond to the magnetic field of a companion member energized by alternating current which includes exposing said element to said field to move the element to a predetermined position in said field and thereafter reducing the strength of the field effective on said element by moving the element to a predetermined position beyond its last previous position.
